UNITED STATES PATENT OFFICE.

GEORGE SAMUEL ANDRES, OF CHICAGO, ILLINOIS.

ATTACHING DEVICE.

Application filed October 6, 1919. Serial No. 328,871.

To all whom it may concern:

Be it known that I, GEORGE SAMUEL ANDRES, a citizen of the United States, and a resident of the city of Chicago, in the county 5 of Cook and State of Illinois, have invented certain new and useful Improvements in Attaching Devices; and I do hereby declare that the following is a full, clear, and exact description of the same, reference being had 10 to the accompanying drawings, and to the numerals of reference marked thereon, which form a part of this specification.

This invention relates to attaching devices, and although not restricted to such use 15 is particularly adapted for use in securing together the two halves of the crank case and other parts of an internal combustion engine.

Heretofore such parts have been connected 20 by means of bolts passed through lugs on the two parts. This is not only a complicated method of attachment, but also one which requires considerable time to attach and detach.

One of the objects, therefore, of the 25 present invention is to provide a simple and readily connected and disconnected form of attachment.

Another object of the invention is to provide a simple form of shackle for releasably connecting two parts together.

Other and further important objects of 30 this invention will be apparent from the disclosures in the specification and drawings.

The invention (in a preferred form) is 35 illustrated in the drawings and hereinafter more fully described.

On the drawings:

Figure 1 is a side view of an internal com- 40 bustion engine embodying the features of the present invention.

Figure 2 is a plan view of the lower half 45 of the crank-case of the same.

Figure 3 is an end view of the lower half 50 of the crank-case, taken on the line 3—3 of Figure 2.

Figure 4 is an end view of the engine 55 shown in Figure 1.

Figure 5 is an enlarged end view of the

lower half of the crank case taken on the 50 line 5—5 of Figure 2.

Figure 6 is an enlarged section on the line 6—6 of Figure 1.

As shown in the drawings:

The invention is illustrated in connection 55 with an internal combustion engine having a cylinder head 1, cylinder 2, upper crank case 3 and lower crank case 4.

As shown, the two halves of the crank case are connected by means of shackles 5. 60 Each shackle is pivotally mounted in a bracket 6 connected to the lower crank case 4. On each shackle is pivotally mounted a pawl 7, adapted to engage a shoulder 8 on a projection 9 on the upper crank case 3. 65 The operative face of this shoulder is preferably arranged to lie in a plane tangential to the circle described by the pawl turning about the shackle when the latter is in engaging position. With such a construction 70 the pawl and shackle may be brought into and out of engagement with the shoulder 9 without producing any strain in these parts or any parts associated therewith.

The two parts of the crank case are kept 75 in alinement and a tight joint maintained therebetween by providing a groove 10 in the upper crank case 3, into which the edge of the lower crank case projects. A strip of packing 11 is arranged at the bottom of the 80 groove to seal the joint.

The method of connecting the cylinder head and the cylinder is exactly analogous to that just set forth so that further description is unnecessary.

I am aware that numerous details of construction may be varied through a wide range without departing from the principles of this invention, and I therefore do not purpose limiting the patent granted otherwise than necessitated by the prior art.

I claim as my invention:

1. An attaching device including a pivoted shackle, a pawl pivotally mounted thereon and a boss cast integral with one of the 95 members to be fastened, said pawl having two flat surfaces tangent to circles with centers at the axis of the pawl, said surfaces

making an angle of approximately ninety degrees and engaging in the locked position with complementary surfaces on the boss.

2. An attaching device including a pivoted shackle, a pawl pivotally mounted thereon, and a boss integral with one of the parts to be fastened, said pawl having two flat surfaces which engage with complementary surfaces on the boss, the edge formed by these 10 surfaces lying outside of a line joining the

two pivots when in locked position, so as to get an attachment stable even under conditions of excessive vibration.

In testimony whereof I have hereunto subscribed by name in the presence of two 15 subscribing witnesses.

GEORGE SAMUEL ANDRES.
